UNITED STATES PATENT OFFICE.

GEORGE M. GITHENS, OF BROOKLYN, E. D., NEW YORK.

ROCK-DRILL.

SPECIFICATION forming part of Letters Patent No. 247,819, dated October 4, 1881.

Application filed May 16, 1881. (No model.)

To all whom it may concern:

Be it known that I, GEORGE M. GITHENS, of Brooklyn, E. D., in the county of Kings and State of New York, have invented an Improvement 5 in Rock-Drills, of which the following is a specification.

Rock-drills have been driven by steam or compressed air acting within a cylinder upon a piston that is connected with the drill, and 10 in these machines the cylinder has been moved along for feeding by the action of a screw, and the screw has been operated upon by the piston acting against a tappet and giving a movement to a rod or lever that is provided with a 15 pawl that moves a ratchet-wheel attached to the nut of the screw. In this instance the pawl and ratchet-wheel are liable to injury, because there is a very sudden movement given by the 20 piston, and the inertia of the parts has to be overcome.

My improvement is for overcoming this difficulty, and it relates to a means for simply unlatching the screw or nut, instead of turning it, and then allowing the movement of the cylinder endwise to cause the rotation of the screw or nut by the inclined-plane action. This 25 allows a more gradual movement of the parts. It prevents the severe concussion on the pawl and ratchet-teeth, and it insures greater durability in the parts, and a more uniform feeding movement.

In the drawings, Figure 1 is a longitudinal section of the cylinder and valve and elevation of the piston and screw. Fig. 2 is an end view 35 of the cylinder, and Fig. 3 shows the pawl for holding the screw from turning backwardly.

The cylinder *a*, piston *b*, drill-holding piston-rod *c*, and valve *d* are of any usual character.

My Patent No. 212,598 describes a valve 40 somewhat similar to that represented herein. Any novelty in the present valve I reserve for a separate application. I also remark that the piston and drill are partially revolved between each stroke, so as to cause the drill to strike properly upon the rock, and for this purpose any suitable device is employed. The screw *e* is for feeding the cylinder along as the drilling progresses. In some machines the nut *f* is at the cylinder, and the same is revolved, the screw 45 remaining stationary. In other machines the screw is revolved by hand and the nut remains

stationary. If the nut is held by the frame or legs that support the parts in position, the same may be provided with a pinion and crank, by means of which the nut can be turned back 55 to run the cylinder and drill away from the rock. These parts, however, are not further described or claimed herein. If the screw is stationary and the nut revolves, then the portion *f* on the drawings will represent the nut, 60 and *k* the locking-wheel thereof in the form of a flange around one end of the nut. If the screw itself is revolved and the nut stationary in the supports of the drill, then the part *f* will represent a head or hub upon the screw, and 65 formed as one piece therewith or permanently connected, and the locking-wheel *k* will be a part thereof.

The rock-shaft *l* passes along parallel to the axis of the cylinder. At its inner end there is 70 a foot, *m*, against one side of which the incline or tapering portion of the piston *b* acts to partially turn the rock-shaft *l*.

n is an arm on the shaft *l* outside the cylinder, and *o* is a blocking-pawl binged to its end. 75 The spring *p* presses the swinging end of *n* and the pawl *o* toward the blocking-wheel *k*. This blocking-wheel has one, two, or more notches around its periphery adapted to receive the end of the pawl *o*. An inclined stud, 80 *r*, is at the back of the blocking-pawl *o*, and there is a spiral or other spring, *v*, therein.

When the rock-drilling is progressing the cylinder *a* is presumed to remain immovable and the piston and rod reciprocate. When the 85 drilling has progressed sufficiently for the incline upon the piston to touch the toe *m* and turn the rock-shaft the pawl *o* will be drawn back out of contact with the blocking-wheel, and the spring *v* will move such pawl *o* away 90 from the stud *r*, so that the pawl *o* cannot re-enter the notch in the wheel *k*. The wheel *k* is now free to turn, and the steam or air acting in the cylinder to raise the piston and drill also acts to move the cylinder toward the rock, 95 and the incline of the nut and screw will move against each other, causing the rotation or partial rotation of the wheel *k* and screw or nut, and thereby allowing the cylinder to move until arrested by the pawl *o* entering the next 100 notch in the wheel *k* and blocking the further movement until the further drilling of the rock

allows the piston to move until it again strikes the toe *m* and withdraws the blocking-pawl, and the operations are repeated.

In some instances I make use of a compound 5 conical incline around the piston, as at 2 and 3, the portion 2 operating the valve and the portion 3 operating the toe *m*, as the toe will not project into the cylinder as much as does the valve; hence the part 3 will act either on 10 the valve or the toe and the part 2 will only act on the valve. The part 3 should only extend about half around the piston, and therefore the toe can only be operated upon during that portion of the rotary and reciprocating 15 movement of the drill and the piston when said part 3 is adjacent to the toe *m*, and the feed cannot take place oftener than once each revolution of the drill.

In operating all rock-drills by direct action 20 of steam, the tendency of the pressure is to move the cylinder in one direction, and the piston and drill in the other direction; and this produces a violent concussion of the screw endwise upon the nut, or of the nut upon the 25 screw, if the thread has worn loose. To prevent this undesirable movement I employ a self-acting lock-nut, *w*, that surrounds the screw. It is made of steel, and as the screw or nut is shaken endwise by the reciprocations 30 this nut acts by gravity, and, sliding down the incline of the screw, intervenes as a wedge, to prevent end movement and looseness. This lessens wear by preventing end movement and concussion, and when applied to screws already worn loose, it allows them to be kept in 35 use much longer before the screw is worn out.

In most instances it is important to prevent the screw or the nut turning back the wrong way when the blocking-pawl is liberated, and 40 also to prevent any tendency to press back the blocking-pawl by the inclined portion of the notches in the wheel *k*. To provide for this a ratchet-wheel, *w'*, and holding-pawl *t* are applied to the screw or nut, as seen in Figs. 1

and 3. A friction-clamp or any similar means 45 may be substituted for the holding-pawl.

A lever may take the place of the rock-shaft and arm, such lever having the toe at one end and being connected to the locking-pawl at the other end. 50

I claim as my invention—

1. The combination, with the cylinder and piston in a rock-drill, of a screw and nut, a blocking-wheel, and a pawl or latch, and means for withdrawing such pawl or latch, so as to 55 allow the screw or nut to turn by the endwise movement of the cylinder as acted upon by the power, substantially as set forth.

2. The combination, in a rock-drill, of the cylinder *a*, piston *b*, toe *m*, rock-shaft *l*, arm *n*, 60 blocking-pawl *o*, wheel *k*, screw, and nut, substantially as set forth, whereby the blocking-pawl is moved out of action by the piston, for the purposes specified.

3. The combination, with the screw and nut 65 in a rock-drill, of a notched blocking-wheel, pawl or latch mechanism for withdrawing the same, and a spring to prevent the pawl or latch immediately re-entering the notch in the wheel, substantially as set forth. 70

4. The combination, with the screw and nut in a rock-drilling machine, of a loose wedge-acting lock-nut, for the purposes and as set forth.

5. The combination, with the screw and nut 75 in a rock-drilling machine, of a rock-shaft and toe or their equivalents, and a piston having an incline on its surface extending partially around it to act upon the toe when the piston is turned into the proper position, the piston 80 not acting on the tappet during a portion of its revolution, substantially as set forth.

Signed by me this 4th day of May, A. D. 1881.
